United States Patent Office

Des. 200,822
Patented Apr. 6, 1965

200,822

CAMERA

William A. Messina, West Englewood, N.J., assignor to
Fotochrome, Inc., Long Island City, N.Y.

Filed Feb. 6, 1964, Ser. No. 78,541

Term of patent 14 years

(Cl. D61—1)

FIG. 1

FIG. 2

FIG. 3

Des. 200,822

PAGE 2

FIG. 4

FIG. 5

FIG. 6

FIG. 1 is a front elevational view of a camera showing my new design;

FIG. 2 is a side elevational view as seen from the right hand side of FIG. 1;

FIG. 3 is a side elevational view as seen from the left hand side of FIG. 1;

FIG. 4 is a top plan view;

FIG. 5 is a rear elevational view; and

FIG. 6 is a perspective view thereof.

The bottom of the camera, not shown, is substantially plain and unornamented.

I claim:

The ornamental design for a camera, substantially as shown and described.
